(57) **CLAIM**

The ornamental design for a television receiver as shown and described.

DESCRIPTION

The patent or application file contains at least one drawing executed in color. Copies of this patent or patent application publication with color drawing(s) will be provided by the Office upon request and payment of the necessary fee.

1. Television receiver

1.1 : Front perspective view

1.2 : Back perspective view

1.3 : Front

1.4 : Back

1.5 : Left

1.6 : Top

1.7 : Bottom

1.8 : Enlarged

1.9 : Reference view

1.10 : Reference view

1.11 : Reference view

1.12 : Reference view

The characteristic features of the design lie in the shape; reproduction 1.8 is an enlarged view of the encircled portion in reproduction 1.1; the broken lines shown in reproductions 1.1 to 1.8 depict portions of the television receiver and form no part of the claimed design; the dot-dash lines defining the boundary of the enlargement area form no part of the claimed design; reproductions 1.9 to 1.12 show the states of use wherein all other broken lines and colors depict environment and form no part of the claimed design; the shading
